UNITED STATES PATENT OFFICE.

JOSEPH BROWN DAVIS, OF DAYTONA BEACH, FLORIDA.

AERIAL DELIVERY DEVICE.

Application filed January 7, 1927. Serial No. 159,697.

This invention relates to aerial delivery apparatus and its primary object is to provide a simple and efficient apparatus whereby mail as well as other articles can be transferred from the ground to airplanes or the like thereby overcoming the necessity of the airplane landing for that purpose.

A further object of the invention is to provide an aerial delivery apparatus that contains very few parts, is inexpensive to manufacture and will perform its intended function for an indefinite period of time.

This invention also consists in certain other features of construction and in the combination and arrangement of the several parts, to be hereinafter fully described, illustrated in the accompanying drawings and specifically pointed out in the appended claim.

20 In describing my invention in detail, reference will be had to the accompanying drawings wherein like characters denote like or corresponding parts throughout the several views, and in which:

25 Figure 1 is a side elevation of the apparatus forming the subject matter of the present invention and showing the airplane about to receive a bag therefrom.

Figure 2 is a top plan view thereof.

30 Figure 3 is a fragmentary view showing the clamping member and the adjacent ends of the guide rails in section.

Figure 4 is a perspective view of the adjacent ends of the guide rails.

35 Figure 5 is a similar view of the clamping member per se.

Figure 6 is a detail view of the cable weight.

Referring to the drawings in detail the 40 reference numeral 1 indicates the guide rails for the apparatus and as best shown in Figure 2 in the drawings these rails have outwardly flared portions 2 and parallel portions 3 extending in close proximity. The

45 ends of the flared portions are arranged on the ground or other supporting means and fixed thereto through the medium of bracket members 4. The remaining portions of the rails are elevated and supported in said ele-

50 vated position by braces, two pair of which are indicated by the reference numeral 5 and include upwardly and inwardly inclined portions having their upper ends secured to the rails and their lower portions fixed in

55 bases 6. The remaining or forward brace as shown is indicated by the reference

numeral 5" and will be later described. A grating is arranged to underlie the braces 5 and extends from the outer lower edges of the rails to the bases 6 as clearly shown in Figures 1 and 2 of the drawings.

The parallel portions 3 terminate in right angled bent apertured ends 3' having pivotally secured thereto as at 4', arms 5' which have inwardly projecting flanges 6' formed on their upper and lower edges, and these flanges 6' have their rear portions curved outwardly to provide guiding surfaces which merge into the arms as best shown in Figures 3 and 4 of the drawings. The front end of the flanges terminate with the free ends of the arms and provide channels 7 arranged in confronting relation to co-operate for frictionally receiving a substantially U-shaped clamping member 8 having a circular bight portion and parallel arms 9 and 10. The forward pair of braces 5" is constructed to allow pivotal movement of the arms 5' and includes slotted angle sections 7' having their upper ends secured to the arms 5' adjacent their free ends as best shown in Figure 4 of the drawings and these sections 7' are mounted for slidable movement on the vertical portions of sections 8' from which extend headed pins 9' arranged in the slots formed in the sections 7' to limit the upward movement of the arms 5' on their pivots 4'. The sections 8' extend from the forward base 6 as clearly shown in Figure 2 of the drawings. By this construction, it will be apparent that the arms 5' are capable of movement in a vertical plane and can be moved upwardly approximately to a forty-five degree angle with respect to the parallel portions 3' as shown in dotted lines in Figure 1 of the drawing.

As best shown in Figure 3 of the drawings, the arm 10 of the clamping member is substantially hollow and pivotally secured to said hollow portion is a pawl 13 having a projection 14 extending from its pivoted end and said projection is engaged by a leaf spring 15 which is secured to a shoulder 16 formed in the arm 10 and is adapted to normally retain the pawl 13 in a position to bridge the space between the arms 9 and 10. Hingedly secured to the exterior surface of the circular portion 11 of the U-shaped member is one end of a curved strap 17 of a locking means. The opposite end of the curved strap is recessed as at 18 to receive a keeper 19 extending from the clamping

member so that a lock 20 of the shackle type can be positioned in the keeper and retain the strap operatively associated therewith as will be readily apparent.

- 5 From the above description and disclosure in the drawings, it will be obvious that when it is desired to transfer a bag of mail or any other articles from the ground to a moving airplane or the like, the transferred 10 article is clamped to the clamping member 8 through the instrumentality of the strap 17 and its locking means 19 and 20, and the clamping member 8 is positioned in the channels 7 as best shown in Figure 3 of the 15 drawings so that a cable 21 which has one end secured in the airplane can pass freely between the arms 9 and 10 thereof after being guided by the rails thereto. The cable is provided with a weight 22 on its free end 20 so that it will be drawn by gravity as will be apparent and when the cable is positioned in the opening 12, it cannot be casually removed therefrom due to the fact that the pawl 13 bridges the space between the arms 25 9 and 10 and the weight being of a size so that it cannot pass through the opening. The further movement of the airplane will cause the weight to pull the clamping member together with its bag, from the channel 30 7 and thence the clamping member and its bag can be drawn up into the plane by a windlass or other means (not shown).

It is thought from the foregoing description that the advantages and novel features of my invention will be readily apparent. 35

I desire it to be understood that I may make changes in the construction and in the combination and arrangement of the several parts, provided that such changes fall within the scope of the appended claim. 40

What I claim is:

In an aerial delivery device cooperating outwardly flared guide rails, arms pivotally secured to the adjacent ends of said rails and including channel portions, means including slidably related sections for supporting said arms, an article carrying means arranged in the channel portions and including a substantially U-shaped member having a substantially circular bight portion and parallel arms, one of said arms being hollow, said arms being adapted to be frictionally held in the channel portions, a spring pressed pawl normally positioned across the space between the arms of the U-shaped member and pivotally secured in the hollow arm, a strip having one end pivoted to the bight portion of said substantially U-shaped member and adapted to secure an article thereto, and said article carrying means being adapted to be removed by an aerial conveying means. 50 55 60

In witness whereof I affix my signature.
JOSEPH BROWN DAVIS.
